SKATE SHARPENER

Ernest J. Toms, Welland, Ontario, Canada

Application August 21, 1958, Serial No. 756,359

1 Claim. (Cl. 51—214)

This invention relates to skate sharpening devices.

Various types of skate sharpeners have heretofore been proposed. Most of such sharpeners consist of a multiplicity of parts and are difficult to adjust and awkward to use.

It is an object of this invention to provide a skate sharpener having a minimum number of parts, which is inexpensive to manufacture, which can be readily adjusted to maintain the sharpening surface in uniform relation to the skate at all times, and which is easy to operate.

The invention relates to a skate sharpener comprising a single unitary rectangular metal block having a groove in one longitudinal face thereof, and a cylindrical recess of greater diameter than the width of said groove extending longitudinally of the block from end to end thereof and communicating throughout its length with the base of said groove, said recess forming shoulders in said block extending outwardly of the lower edges of said groove, a rod of abrasive material in said recess, said rod having an arcuate surface of smaller radius than that of said recess constituting the bottom wall of said groove, and adjustable clamping means engaging said rod to hold the same in seating engagement with said shoulders.

The invention will be described with reference to the accompanying drawing, in which:

Figure 1 is a side elevation of a skate sharpener in accordance with the invention,

Figure 2 is an end elevation, and

Figure 3 is an end elevation of a slightly modified form of sharpener.

Referring to Figures 1 and 2, 1 is a block of metal, preferably light weight metal such as aluminum or magnesium alloys. The block has a length of about four or five times its width, and a depth from one and one-half to twice its width. Thus the block may be approximately four inches long, three-quarters of an inch in width, and one and one-quarter inch in depth. The block has plane uninterrupted side faces 2, plane unobstructed end faces 3 and top face 4, as well as a plane bottom face 5.

A groove 6 is formed in the top face 4 and extending from end to end thereof in parallel relation to the side faces 2. The groove has a depth of approximately one-half inch and a width of approximately one-eighth to one-quarter inch.

A cylindrical recess 7 extends from end to end of the block and communicates with the base of the groove 6, the recess having a diameter greater than the width of the groove 6. Thus, a diameter of approximately

2

one-half inch is satisfactory. The recess thus provides a shoulder 8 extending outwardly from each inner edge of the groove and having an arcuate surface. In the recess 7 is a rod 9 of abrasive material such as that known under the trade name "Carborundum." The rod 9 extends from end to end of the recess and, in the modification shown, is semi-cylindrical in cross section. The arcuate surface 10 of the rod is adapted to be seated upon the arcuate shoulders 8 and the radius of such surface 10 is slightly less than that of the shoulders 8 whereby a firm seating engagement may be provided at all times.

Means for holding the rod 9 in the seating position described comprises a pair of set screws 11 extending inwardly from the bottom face 5. The screws 11 have threaded mounting in the block 1 and the ends thereof extend into the recess 7 for applying pressure on the flat under surface 12 of the rod. A bearing plate 13 may be interposed between the ends of the screws and the rod. The screws 11 may be spaced about two inches apart to provide adequate support for the rod 9. Preferably the heads 14 of the screws are countersunk as indicated to provide an unobstructed bottom face 5.

Referring to Figure 3, the modification therein illustrated is similar to that shown in Figures 1 and 2 with the exception that an abrasive rod 15 of circular cross section is substituted for the rod 9. As before, the radius of rod 15 is less than that of the recess 7.

Preferably, the corners of the block at the mouth of the groove 6 are bevelled as indicated at 16 to provide space for reception of the tube of a tube skate. This is an important consideration since tube skates are in widespread use.

I claim:

A skate sharpener comprising a single unitary rectangular metal block having a groove in one longitudinal face thereof, and a cylindrical recess of greater diameter than the width of said groove extending longitudinally of the block from end to end thereof and communicating throughout its length with the base of said groove, said recess forming shoulders in said block extending outwardly of the lower edges of said groove, a rod of abrasive material in said recess, said rod having an arcuate surface of smaller radius than that of said recess and constituting the bottom wall of said groove, and adjustable clamping means engaging said rod to hold the same in seating engagement with said shoulders and comprising a bearing plate in said groove, said rod having a surface opposed to said arcuate surface in engagement with said bearing plate, and screws in said block each having an end in pressure-applying engagement with said bearing plate.
